J. H. M. LIPP.

NECKWEAR.

APPLICATION FILED OCT. 15, 1917.

1,300,179.

Patented Apr. 8, 1919.

UNITED STATES PATENT OFFICE.

JULIUS H. M. LIPP, OF BUFFALO, NEW YORK.

NECKWEAR.

1,300,179.

Specification of Letters Patent.

Patented Apr. 8, 1919.

Application filed October 15, 1917. Serial No. 196,682.

To all whom it may concern:

Be it known that I, JULIUS H. M. LIPP, a citizen of the United States, residing at Buffalo, in the county of Erie and State of New York, have invented certain new and useful Improvements in Neckwear, of which the following is a specification.

This invention has to do with improvements in articles of neckwear, generally known as mufflers or scarfs.

The primary object in view is to provide means for positively holding the muffler in position, such means being engageable over the usual linen collar attached to the shirt of the wearer, so as to preclude against accidental displacement of the muffler with the resultant soiling of the collar by the overcoat or other outer garment. Broadly, it is comprehended that the invention may be in the form of an attachment constituting a part of the muffler or in the form of an article of manufacture that may be purchased for application to a muffler as may be desired.

To this end the invention consists in the combination, and arrangement of parts more fully set forth and described herein-after in the specification and claims and illustrated in the accompanying drawings, wherein:

Figure 1 is a plan view showing a form of the device embodying a tab arrangement;

Fig. 2 is a perspective view of the adjustable tab disclosed in Fig. 1;

Fig. 3 is a perspective view of a modified form of the invention;

Fig. 4 is a front elevation of the device as shown in Fig. 3; and

Fig. 5 is a vertical sectional view showing the application of the device shown in Figs. 3 and 4.

Referring to Figs. 1 to 3 of the drawing, 1 designates a scarf of conventional form, generally known as a muffler, which is designed to be interposed between the linen collar attached to the shirt of a wearer and an overcoat for the purpose of preventing the collar from being soiled. A muffler of this type is subject to displacement during the wearing of the same or in putting on of the overcoat and it is the object, as hereinbefore premised, of this invention to pro-

vide means for retaining the muffler in place whether the outer coat is fastened together or allowed to remain open.

Referring to the form of the holding device illustrated in Figs. 1 and 2, it will be observed that I employ a tab as indicated at 2' provided with a flexible element 4 stitched to the upper edge of the tab, which latter flexible element is preferably provided with some fastening means for connection of the tab to the scarf 1. In the form mentioned the fastening means illustrated are the usual snap fasteners, one part 5 of which is connected to the flexible element of the tab and the other part 6 to the scarf. There are preferably a plurality of these snap fasteners used, arranged in spaced relation, and the part 6 thereof may be secured to a stiffening base 7 which in turn is attached to the scarf. The stiffening base 7 provides a ready means of attachment of the fastener to the scarf and in addition constitutes a piece to hold the upper edge of the scarf against turning outwardly and showing the fastener when the article is in use. By virtue of the use of a plurality of these fastening elements one of the tabs shown in Fig. 1 may be adjusted in a direction longitudinally of the scarf end while the other tab which is indicated at 2'' is similarly provided with a flexible connection 4' and permanently stitched to the scarf.

The adjustment of the adjustable tab is provided so that the device may be used by wearers having different sized collars, and furthermore the position of the tab may be adjusted according to whether the wearer wishes to have the muffler tightly closed in front or allowed to remain slightly open.

The device which forms the subject matter of this invention may be further modified so as to constitute an article of manufacture which may be purchasable upon the market for attachment to a muffler to perform the object hereinbefore referred to. Under such condition the attachment would take the form of a clip illustrated in Figs. 3, 4, and 5, said clip having the spring 10c clamping jaw 8 at one side and the bent yieldable clamp 9 at the other side. It is preferred that the lip or extremity of the spring clamping element 8 be curved over

the top of the collar engaging element 9 as indicated at 10 so as to prevent damage to the scarf to which it is applied. In the use of this arrangement the edge of the scarf is engaged between the jaws of the spring clamp 8 while the collar engaging portion 9 is slipped over the shirt collar in the manner indicated clearly in Fig. 8. Such arrangement of the device partakes of adjustability, 10 as will be apparent according to the desire of the wearer, and will readily hold the muffler in the various positions which may be desirable.

In applying the muffler in position the 15 tabs are disposed over the shirt collar, speaking with reference to the particular form of the device shown in Fig. 1, and between the neck of the wearer and the said collar. As the tabs are arranged in spaced 20 relation the muffler will be held positively in its proper position preventing contact of the outer coat with the collar. The tabs referred to are preferably made of stiff material and may be of any suitable size for carrying out the function specified.

As it is possible to employ various other forms of fastening means than the snap fastening arrangement hereinbefore described, I do not wish to be confined to this particu- 25

lar method of attaching the device to the 30 muffler.

Having thus described my invention, what I claim as new is:—

1. The combination with a scarf or the like, of a fastener for holding the same in 35 place upon a collar, comprising a collar engaging portion at one side freely engageable over and shiftable about the collar, and a scarf engaging portion at the other side engageable with the scarf at the under side so 40 as to lie intermediate the outer surface of the collar and the said scarf under side, said scarf engaging portion having positive engagement with the scarf permitting of adjustment at will with respect to the scarf 45 without displacement of the scarf.

2. The combination, with a neck scarf or similar article of wear having one of its edges provided with fastening means, of spaced holding members engageable over 50 the usual collar upon the wearer's shirt so as to hold the scarf at points at opposite sides of the neck, and means for adjustably connecting one of said members to the scarf fastening means aforesaid.

55 In testimony whereof I affix my signature.

JULIUS H. M. LIPP.
